MAURICE RATEL, OF NEW YORK, N. Y.

AUTOMATIC STOKER.

Application filed February 20, 1922, Serial No. 538,004, and in France February 25, 1921.

This invention relates to automatic stokers, and more particularly to automatic underfeed stokers of the type wherein the fuel and solid products of combustion are fed down an inclined fuel bed with the aid of gravity.

It has heretofore been proposed to provide an underfeed stoker of the type above referred to comprising a series of alternating fuel retorts or troughs and downwardly inclined twyters, together with means in each of the retorts for feeding fuel therethrough to the fuel bed. In view of the relatively steep inclination of the fuel bed necessary 15 to utilize gravity for moving the fuel and solid products of combustion downwardly, this type of stoker requires considerable space in a vertical direction whereby it is unavailable for use with locomotives or marine 20 boilers where a relatively high fuel bed cannot be installed.

It has further been proposed to provide an automatic underfeed stoker comprising alternating twyters and fuel retorts or 25 troughs successively decreasing in elevation from a medial fore and aft line of the furnace toward the sides thereof, with refuse discharge grates and ash pits at both sides of the furnace. Automatic underfeed stokers 30 of this type have been objected to for use in furnaces of locomotives and marine boilers because of the limited space available to handle the refuse and because the lateral disposition of the refuse handling means 35 has the defect of obstructing free passage of air to the lateral retorts.

It is the object of the present invention to overcome these disadvantages by inclining the fuel bed from the sides of the furnace toward a central or intermediate refuse discharge opening and ash-pit and providing a 40 distribution of fuel to the fuel bed which insures an even thickness from the top to the bottom thereof.

A further object of the invention is to 45 provide a fuel bed substantially V-shaped in cross-section whereby sufficient inclination is had to insure downward movement of the fuel with the aid of gravity, and to progressively decrease the amount of fuel supplied to the fuel bed from the top to the bottom thereof.

A further object of the invention is to insure proper combustion of the fuel by providing the fuel bed with an air supply which

progressively decreases from the sides of the furnace toward a refuse discharge grate positioned at an intermediate part of the furnace.

A further object of the invention is to 60 provide, in combination with an automatic stoker of the type heretofore referred to, devices adapted to convey the fuel from a source of supply to the fuel hoppers and retorts of the stoker.

A further object of the invention is to provide an automatic underfeed stoker of the type heretofore referred to wherein a continuous discharge and removal of the ashes and clinkers is insured.

A further object of the invention is to provide twyters of novel construction which are cooled by air passages of considerable area, circulation of water therethrough, or both.

A further object of the invention is to 75 provide a safety device for the fuel feeding apparatus and driving means therefor whereby, if operation of one or more of the fuel feeding members is for any reason prevented, the driving mechanism and remaining fuel feeding members will continue to 80 operate.

Other objects of the invention relate to the provision of an automatic underfeed stoker which is simple in construction, efficient in operation, and inexpensive to maintain; which provides for maintaining high rates of combustion without danger of destruction of the parts, and the provision of 85 novel features of construction which are 90 adapted for use in any furnace installation.

Broadly stated, the invention comprises an automatic underfeed stoker having a plurality of alternating twyters and fuel retorts or troughs extending longitudinally of the 95 furnace and successively decreasing in elevation from the sides of the furnace toward a central or intermediate refuse discharge opening or chamber, (said retorts preferably having successively decreasing depth or capacity) and providing with the twyters, a fuel bed substantially V-shaped in cross-section down which the fuel and solid products of combustion travel with the aid of gravity, an air supply for the fuel bed which preferably progressively decreases from the up- 100 most twyters to a central grate or grates at the bottom of the fuel bed, and means for supplying and feeding fuel to the fuel bed so constructed and arranged as to decrease 105 110

the amount of fuel supplied from the sides of the furnace toward the center thereof. The means for thus decreasing the supply of fuel from the sides toward the center of the furnace preferably consists of fuel feeding members disposed throughout a major portion of the length of each retort which feed to the fuel bed progressively decreasing quantities of fuel through the successive retorts from the sides of the furnace toward a medial fore and aft line thereof, which fuel feeding members may have progressively decreasing strokes, progressively decreasing capacity, or both, and which produce by their movement an undulatory or wave-like motion to the fuel bed.

The invention is capable of receiving a variety of mechanical expressions, some of which are shown on the accompanying drawings, but it is to be expressly understood that the drawings are for purposes of illustration only and are not to be construed as a definition of the limits of the invention, reference being had to the appended claims for that purpose.

In said drawings, in which the same reference characters designate corresponding parts throughout the several views:

Fig. 1 is a longitudinal section on the line 30 1—1 of Fig. 2, the linkage hereafter designated 35, 36, 37 being shown in elevation for clearness of understanding, and showing an automatic stoker and fuel-conveying mechanism embodying the present invention installed on a locomotive and fuel tender;

Fig. 2 is a schematic plan of the stoker and fuel-conveying apparatus shown in Fig. 1, a portion of said apparatus being broken away for purposes of clearer illustration;

Fig. 3 is an enlarged transverse section on the line 3—3 of Fig. 1, showing the refuse crushing apparatus and central ash-pit the fuel feeding members and refractory arch being omitted;

Fig. 3^a is an enlarged detail of one-half of the fuel support showing the decreasing size of the air openings, the fuel feeding means being omitted;

Fig. 4 is a longitudinal section on the line 50 4—4 of Fig. 5 and shows another embodiment of the present invention installed with a marine boiler, with crushing and evacuation mechanism which ejects the ashes and refuse from the ash-pit;

Fig. 5 is a part section and a part front elevation of the automatic stoker shown in Fig. 4;

Figs. 6, 7 and 8 illustrate respectively a transverse section of an improved twyer, a side elevation of the same, and a similar section with the side and top bars removed;

Fig. 9 is a longitudinal section through parts of such an installation as is shown in Figs. 1 and 3, illustrating a water-cooled twyer;

Fig. 10 is a section through the twyer shown in Fig. 9;

Fig. 11 is a sectional view through one of the fuel feeding members showing a safety slip-connection between the ram and the driving means therefor;

Fig. 12 is an enlarged detail in side elevation of the means for transmitting power from the crank-shaft to the refuse crushing and ejecting devices shown in Figs. 4 and 5; and

Fig. 13 is a fragmentary section on the line 13—13 of Fig. 12.

The present invention is applicable to a wide variety of boilers and forms of furnaces, and therefore, as it is not limited to any particular type of boiler or furnace construction, certain details of the latter have not been illustrated.

In the embodiment shown in Figs. 1 to 3, wherein the automatic stoker of this invention is shown installed in the furnace of a locomotive, the fuel retorts or troughs 1 alternate with the tuyers 2 and successively decrease in depth from the sides of the furnace toward a medial fore and aft line thereof, and the tuyers are stepped downwardly from the sides of the furnace to successively decrease their elevation toward the center of the furnace. The tuyers and retorts preferably comprise two series, one on each side of a medial fore and aft line of the furnace to form a fuel bed substantially V-shaped in cross-section, and the lower part is provided with a plurality of grates 3 adjacent to the lowermost tuyers and disposed on both sides of said medial line to provide a central refuse discharge opening 4 at the bottom of the fuel bed. As clearly shown in Figs. 1 and 3, the ash-pit 5 extends longitudinally of the furnace and is disposed centrally thereof below the refuse discharge opening. Automatic evacuation of the refuse from the ash-pit is, in this case, effected with the aid of gravity by means of spouts 6 on the bottom of the ash-pit. The fuel is fed through each retort 1 by a plurality of fuel feeding members which are of progressively decreasing capacity from the sides toward the center of the furnace and are disposed throughout a major portion of the length of each retort. In the form shown, the fuel feeding members comprise a main fuel feeding member or ram 7 supplied from a hopper 8, and a plurality of secondary pushers 10 carried on a rod 11 having reciprocating motion on the bottom of the retort by connection of the same with the ram 7. The strokes of the fuel feeding means in successive retorts are shown as progressively decreased from the sides toward the center of the furnace and, as shown in Fig. 3, the retorts 1 successively decrease in depth in accordance with the successive decrease in stroke

of the fuel feeding members therein. There is thus provided a fuel feeding means extending substantially throughout the length of each retort and having a progressively decreasing capacity to feed progressively decreasing quantities of fuel through the successive retorts from the sides of the furnace toward the center thereof.

The fuel feeding rams 7 may be driven in any suitable way and, in the form shown in Fig. 2, driving of said rams is effected by means of steam pistons 12, the rods 13 of which are connected to a rod 14 centrally pivoted at 15 to a stationary part of the stoker. The connection between the rod 14, the rods 13, and rods 16 of the feeding rams is effected by means of thrust pins 11 which are disposed for adjustment in openings of said rods whereby the strokes of the rams 7 may be adjusted as desired.

Referring to Fig. 3 the central refuse discharge opening 4 is preferably provided by a grate at the bottom of the fuel bed comprising a plurality of grate sections at the bottom of the lowermost twyers and forming a continuation of the sides of the fuel bed.

In order to insure proper combustion of the fuel, the fuel bed is provided with an air supply which progressively decreases from the sides of the furnace toward the central grates. As shown in Fig. 3, air is supplied from a conduit 17 through apertures in the twyers which progressively decrease in size in each successive twyer (Fig. 3a), and the air supply to the grates is preferably adjusted by a plurality of dampers 18 disposed in suitable openings in the walls of air boxes 19 arranged under the grates.

Any suitable type of automatic means for crushing the cinders and slag or for carrying away the ashes may be employed, the central ash-pit being shown as provided with one or more crushers 20 which receive movement by means of rods 21 actuated by the oscillating rod 14 and levers 22 carrying pawls 23 rotating ratchet wheels 24 which alternately transmit movement to bevel gears 25 and the pinion 26 keyed on the shaft of the crusher.

In accordance with the present invention, there is preferably combined with the automatic stoker means for supplying fuel to the fuel retorts and the fuel feeding members therein. In the embodiment shown in Figs. 1 to 3, the fuel supplying means comprise troughs 27 disposed on the bottom of the fuel tender through which the fuel is fed from the tender to the hopper, or hoppers 8. Each of the troughs 27 is provided at one end with a main fuel feeding member or ram 28 disposed below an opening 29 in the bottom of the fuel tender through which fuel enters the troughs 27 with the aid of gravity. Each of the troughs 27 is pro-

vided with a plurality of secondary pushers 30 secured on a rod 31 reciprocatorily on the bottom of the trough by an adjustable connection with the ram 28. This adjustable connection preferably comprises thrust pins 32 positioned in the desired apertures provided in the end of rod 31 and coacting with an extension 33 on the ram 28. The strokes of the rams 28, the pushers 30 and the various fuel feeding members for the stoker proper may all be relatively adjusted as desired. The rams 28 receive reciprocating movement from the steam pistons 12 by means of a series of articulated rods 34, 35, 36, 37, which oscillate about fixed pivots 38 and 39, the connection between rods 35 and rods 13 being provided by universal joints 40. Each ram 28 is connected with a coal breaker 41 having reciprocating movement across the opening in the bottom of the fuel tender, whereby the fuel is agitated above the opening to prevent obstruction thereof and insure continued feeding of the fuel from the tender into the troughs 27. The conveyor means further comprises a trough section 42 for each trough having one end projecting into the hopper 8 and its opposite end flexibly and slidably connected with the corresponding end of the trough 27 by means of hinged plates 43 connected to the trough section and slidably received by guides 44 on the sides and bottom of the trough 27.

Figs. 4 and 5 illustrate an embodiment of the invention installed in a furnace of a marine boiler. In the present instance a fuel bed substantially V-shaped in cross section is provided by two series of alternating twyers and fuel retorts or troughs. The fuel retorts or troughs 1' alternate with the twyers 2' and successively decrease in depth from the sides of the furnace toward a medial fore and aft line thereof, and the twyers are stepped downwardly from the sides of the furnace to successively decrease their elevation. A plurality of grates 3' are provided at the lowermost twyers, said grates forming continuations of the V-shaped fuel bed inclinations. The grates 3' are disposed on both sides of the medial fore and aft line of the furnace to provide a central refuse discharge opening 4'. An ash pit 5' extends longitudinally of the furnace and is disposed centrally thereof below the refuse discharge opening 4'. The fuel is fed through each retort by a plurality of fuel feeding members of progressively decreasing capacity disposed throughout a major portion of the length of each retort. These fuel feeding members comprise a main fuel feeding member 7' supplied from a hopper 8', and a plurality of secondary fuel feeding members 10' carried on a rod 11' having reciprocating motion on the bottom of the retort by connection of the same with the

ram 7'. The fuel feeding devices are driven by the crank shaft 45 receiving movement from any suitable source of power, for example a speed box 46 and connecting rods 47 transmitting movement to each of the feeding rams and also to the crushing rollers 20' by means of a rod 48 carrying a pawl 49 and the opposite end of the rod being fixed on a shaft 50 carrying a ratchet wheel 51 and bevel gears 52, one of the latter being mounted on the shaft of each crusher. Pawl 49 maintains a driving connection for the above described mechanism by engaging ratchet wheel 51. Automatic discharge and carrying away of the refuse is effected in this embodiment of the invention by conveying means disposed on the bottom of the ash-pit, preferably having the form of a pusher 53 provided with a plurality of pusher elements 54. Said pusher is reciprocated by means of an oscillating lever 55 having a pin and slot connection at one end and a thrust pin connection of the type above referred to with the outer end of the pusher. The thrust pins 56 of said last-named connection are disposed in suitable openings in the end of the pusher whereby the stroke of the latter may be adjusted as desired. The mechanism above described is shown in detail in Figs. 12 and 13.

Figs. 6, 7 and 8 show an improved form of twyler including a plurality of corrugated bars 57 which are detachably secured to the twyler so that, when one or more of the bars 35 is destroyed or rendered unfit for use, the same may be removed and replaced without necessitating removal of the complete twyler. By this construction of twyler, expensive maintenance incident to the twylers heretofore proposed is eliminated. As shown, each twyler is preferably made of a plurality of sections, each section comprising a hollow frame 58 having end plates 59 secured thereto by bolts 60, the plates 59 being provided 40 on their ends and upper edges with dove-tailed slots 61 which receive dove-tailed tenons of side bars 62 and the aforesaid corrugated fuel supporting bars 57, respectively. The corrugated fuel supporting bars, 45 that coact with the sides of frame 58 to provide Venturi passages for air delivered therethrough to the fuel bed, are preferably arranged in stepped relation to provide air spaces 63 therebetween which progressively 50 decrease in size, the total area of said spaces being increased by the corrugations of the bars. This increase in the section of the air spaces enables maintenance of very high combustion rates. The side bars 62 are 55 provided with air passages 64 which diverge inwardly from the sides of the bars, and by their formation reduce the force of the draft air which heretofore has been a considerable disadvantage where a rectangular section of 60 the air passages was employed. The air or 65

oxidizing agent for supporting combustion may be introduced to the fuel bed through a suitable conduit 65 by means of any suitable device such as a fan, and the supply of combustion supporting fluid may be regulated by dampers 66 positioned in the combustion supporting fluid conduit 65.

When the invention is installed with a locomotive, movement of the latter may be utilized to create a forced draft, and referring to Fig. 1 the air is shown as supplied to the conduit 17 through a conduit 67 disposed longitudinally of the locomotive with its forward end open to receive air during movement of the latter. The forward end of this conduit is preferably enlarged to insure a suitable air supply which may be combined with steam supplied by steam jets 68 disposed in the conduit 67 and receiving steam by means of pipe 69 which may be 85 connected with the boiler or exhaust of the steam cylinders.

In accordance with one feature of the present invention, expensive maintenance incident to the twylers heretofore proposed may be eliminated by providing twylers having a water circulation therethrough, and Fig. 9 illustrates a longitudinal section through parts of an automatic stoker such as shown in Figs. 1 and 3, the twylers in this case being composed of water tubes 70 arranged in spaced relation to provide, preferably, graduated air spaces therebetween, the ends of the water tubes being received in the headers of the boiler. Plugs 71 in the outer walls of the headers provide means of access to the interior of the tubes, whereby the same may be cleaned as desired. It will thus be obvious that the life of the twylers will be considerably increased, that a greatly increased heating surface will be provided for the boiler, and the general efficiency of the stoker considerably improved.

In accordance with another feature of this invention, the fuel feeding mechanism is provided with a safety device whereby, if operation of one or more of the fuel feeding members is for any reason prevented, the driving mechanism and the remaining fuel feeding members will continue to operate. Referring to Fig. 11 there is illustrated a device of this character which is applicable to any form of fuel feeding mechanism. The device preferably comprises a slip connection between the connecting rod of the driving mechanism and the fuel feeding member or ram. In the form shown, this slip connection consists of a bushing 72 having one end pivotally connected with the ram 7 and its opposite end slidably connected with the connecting rod 47. The slideable connection between the rod and the bushing is provided by an enlargement 73 on said rod which is received in the bore of the tubular bushing 72 and a cap-nut 74 having a central open-

ing for passage of the rod and screw-threaded on the end of the bushing to provide an abutment for the enlargement 73. The walls of the bushing are provided with diametrically disposed longitudinal slots 75 through which the ends of thrust members 76 extend, the thrust members being pivoted on the bushing and normally maintained in positive connection between the ram and the 10 driving rod by means of springs 77 secured to the ram and the outer ends of the thrust members. If operation of the ram should, for any reason, be prevented, such as an obstruction to its feeding movement, the thrust members 76 will be displaced by the forward thrust of the rod 47, whereby the latter will continue its forward movement, the thrust members being displaced through the slots 75 by the enlargement 73. The length of 20 this enlargement will of course be determined by the length of the stroke of the ram, so that at no time in the movement of driving rod 47 will the thrust members 76 drop behind the enlargement 73. On rearward movement, rod 47 will move the ram therewith, the thrust members 76 dropping through the slots 75 to a position in front of the enlargement 73. If the obstruction has been removed, the ram will move forward 30 with the driving rod on the next cycle, the springs 77 being of sufficient strength to normally maintain a rigid connection between the two members.

While the foregoing embodiments of the 35 invention have been described with considerable particularity, it is to be expressly understood that changes in the construction, arrangement and proportion of parts are contemplated within the scope of this invention. It will also be understood that certain 40 features of the invention may be used in other suitable types of automatic stockers and furnaces; that features of the invention shown in connection with one or more embodiments thereof may be used in other embodiments; that features of the invention 45 shown in each embodiment thereof may be used without other features of the same embodiment; and that reference should therefore 50 be made to the claims for a definition of this invention.

What is claimed is:—

1. In an automatic underfeed stoker, a plurality of twyers successively decreasing in elevation from the sides of the furnace toward a medial fore and aft line thereof, fuel retorts or troughs on both sides of said medial line, and means for feeding fuel through said retorts to said twyers.
2. In an automatic underfeed stoker, a plurality of twyers successively decreasing in elevation from the sides of the furnace toward a medial fore and aft line thereof, fuel retorts or troughs alternating with said 55 twyers, and means for feeding progressively

decreasing quantities of fuel through the successive retorts from the sides of the furnace.

3. In an automatic underfeed stoker, a plurality of twyers successively decreasing 70 in elevation from the sides of the furnace toward a medial fore and aft line thereof, fuel retorts or troughs on both sides of said medial line, and a reciprocating fuel pusher in each of said retorts for feeding fuel 75 through the retorts or troughs to said twyers.

4. In an automatic underfeed stoker, a plurality of twyers successively decreasing 80 in elevation from the sides of the furnace 80 toward a medial fore and aft line thereof, fuel retorts or troughs alternating with said twyers, and fuel feeding devices having relative decreasing strokes for feeding progressively smaller quantities of fuel through the 85 successive retorts or troughs toward said medial line.

5. In an underfeed stoker, a plurality of twyers successively increasing in elevation from an intermediate line toward the sides 90 of the furnace, fuel retorts or troughs, interposed between said twyers, and means in said retorts for feeding fuel through the retorts to said twyers.

6. In an underfeed stoker, a series of twyers successively increasing in elevation from an intermediate line toward the sides of the furnace, fuel retorts or troughs alternating with said twyers and successively increasing in cross-section from said medial line 100 toward the sides of the furnace, and means for feeding fuel through said retorts or troughs.

7. In an underfeed stoker, a series of twyers successively increasing in elevation from an intermediate line toward the sides of the furnace, fuel retorts or troughs alternating with said twyers, and fuel-feeding devices successively increasing in capacity from said intermediate line toward the sides of the 110 furnace for feeding progressively increasing quantities of fuel through the successive retorts or troughs on both sides of said intermediate line.

8. In an underfeed stoker, a plurality of twyers successively decreasing in elevation from the sides of the furnace toward an intermediate line, fuel retorts or troughs alternating with said twyers, said twyers and retorts providing a fuel bed, and means for feeding fuel through said retorts to said fuel bed adapted to decrease the supply of fuel from the sides toward the center thereof.

9. In an automatic underfeed stoker, a plurality of twyers successively decreasing 125 in elevation from the sides of the furnace toward a medial fore and aft line thereof, fuel retorts or troughs alternating with said twyers, and means for feeding fuel through said retorts to said twyers.

10. In an automatic underfeed stoker, a fuel bed comprising a plurality of alternating twyers and fuel retorts extending longitudinally of the furnace, said twyers successively decreasing in elevation from the sides of the furnace toward a medial fore and aft line thereof, and means for feeding fuel through said retorts to said fuel bed.
11. In an automatic underfeed stoker, a fuel bed comprising a plurality of twyers stepped downwardly from the sides of the furnace toward a medial fore and aft line thereof and a plurality of retorts alternating with said twyers and having progressively decreasing capacity from the sides of the furnace toward said medial line, and means for feeding fuel through said retorts to said fuel bed.
12. In an automatic underfeed stoker, a plurality of oppositely disposed retorts extending longitudinally of the furnace and successively decreasing in depth and capacity from the sides of the furnace toward a medial fore and aft line thereof, twyers on both sides of said retorts, and means for feeding fuel through said retorts to said twyers.
13. In an underfeed stoker, a V-shaped fuel bed, and means in successive portions of each inclined side of said fuel bed for supplying fuel thereto in successively decreasing quantities from the top to the bottom of the fuel bed.
14. In an automatic underfeed stoker, a V-shaped fuel bed provided at the bottom thereof with a refuse discharge opening, said fuel bed comprising a fuel retort or trough at each side of the medial fore and aft line of the furnace, twyers at the sides of each retort and successively decreasing in elevation from the sides of the furnace toward said refuse discharge opening, and means for feeding fuel through said retorts to said twyers.
15. In an automatic underfeed stoker, a fuel bed comprising two oppositely disposed series of alternating twyers and retorts extending longitudinally of the furnace, the twyers of each series successively decreasing in elevation from a side of the furnace toward a medial fore and aft line thereof, means for feeding fuel through said retorts to said fuel bed, a grate at the bottom of said fuel bed, and means at the bottom of said grate for crushing and discharging the solid products of combustion.
16. In an automatic underfeed stoker, two oppositely disposed series of alternating twyers and retorts extending longitudinally of the furnace, the twyers of each series successively decreasing in elevation from a side of the furnace toward a medial fore and aft line thereof, means for feeding fuel through said retorts to said twyers, a plurality of grates adjacent the lowermost twyers, means at the bottom of said grates for automatically discharging the solid products of combustion, and an adjustable air supply for said grates.
17. In an automatic underfeed stoker, a fuel bed provided with a central refuse discharge opening and comprising two oppositely disposed series of alternating twyers and retorts extending longitudinally of the furnace, the twyers of each series successively decreasing in elevation respectively from a side of the furnace toward said refuse discharge opening, and means for feeding fuel in a longitudinal direction through said retorts to said fuel bed.
18. In an automatic underfeed stoker, a plurality of alternating twyers and retorts successively decreasing in elevation respectively from the sides of the furnace toward a medial fore and aft line thereof, means for feeding fuel through said retorts to the fuel bed, a plurality of grates at the center of said fuel bed and forming a continuation thereof, and an air supply for the fuel bed progressively decreasing from the lateral parts thereof to the central grates.
19. In an automatic underfeed stoker, a plurality of alternating twyers and retorts, said twyers successively decreasing in elevation from the sides of the furnace toward a medial fore and aft line thereof, said twyers and retorts providing an inclined fuel bed, and means for feeding to the fuel bed progressively decreasing quantities of fuel through successive retorts from the sides of the furnace toward the medial fore and aft line thereof.
20. In an automatic underfeed stoker, a plurality of oppositely disposed retorts extending longitudinally of the furnace and successively decreasing in capacity toward the center thereof, a plurality of twyers on both sides of said retorts, said twyers and retorts providing an inclined fuel bed, and means for feeding fuel through said retorts to said fuel bed comprising main and secondary reciprocating members, said secondary members being disposed substantially throughout the length of the retorts.
21. In an automatic underfeed stoker, a plurality of oppositely disposed retorts extending longitudinally of the furnace and successively decreasing in capacity from the sides of the furnace toward the center thereof, twyers on both sides of the retorts and providing therewith a V-shaped fuel bed, reciprocating means for feeding fuel through said retorts to said fuel bed, and means for adjusting the stroke of said reciprocating means.
22. In combination with a furnace, a V-shaped fuel bed extending longitudinally of the furnace and having a refuse discharge opening at the bottom thereof, said fuel bed comprising a fuel retort or trough at each

side of the medial line and of the furnace, twyers at both sides of said retorts and successively decreasing in elevation from the sides of the furnace toward said medial line, 5 means for feeding fuel through said retorts to said twyers, and a refuse chamber arranged below said refuse discharge opening and provided with means for ejecting the refuse delivered through said opening 10 from said fuel bed.

23. In combination with a furnace, a V-shaped fuel bed extending longitudinally of the furnace and having a refuse discharge opening at the bottom thereof, said fuel bed 15 comprising oppositely disposed series of alternating twyers and retorts, said twyers successively decreasing in elevation from the sides of the furnace toward said refuse discharge opening, means adapted to feed fuel 20 through said retorts to said fuel bed, and a refuse discharge chamber arranged below said refuse discharge opening.

24. In combination, a furnace provided with a central refuse discharge passage, an 25 inclined fuel bed in said furnace comprising oppositely disposed series of alternating twyers and retorts extending longitudinally of the furnace, said twyers successively decreasing in elevation from the sides of the 30 furnace toward said refuse discharge passage, reciprocating means for feeding fuel through said retorts to said fuel bed, crushing means arranged in said refuse discharge passage and connected with said fuel feeding means to be operated thereby, and means 35 for regulating the motion of said fuel feeding means and said crushing means.

25. In an automatic stoker, a fuel retort or trough and a sectional twyer disposed adjacent thereto, each twyer section comprising a hollow frame and a plurality of spaced corrugated fuel supporting bars carried thereby, said bars being detachably secured on said frame independently of each other 45 and extending in the direction of the length of the twyer.

26. In an automatic stoker, a fuel retort or trough and a sectional twyer disposed adjacent thereto, each twyer section comprising a hollow frame and a series of separately detachable corrugated fuel supporting bars mounted on said frame and having air spaces therebetween varying in size as respects each other.

55 27. In an automatic stoker, a fuel retort or trough, and a twyer disposed adjacent thereto, said twyer including a hollow frame and a plurality of fuel supporting bars mounted on the frame, said bars and sides of said frame coating to provide Venturi 60 passages for air delivered therethrough to the fuel bed.

28. In an automatic stoker, a fuel retort or trough and a sectional twyer disposed adjacent thereto, each twyer section com-

prising a hollow frame and a plurality of corrugated fuel supporting bars detachably secured on the frame in stepped relation, said bars and sides of said frame coating to provide Venturi passages for air delivered therethrough to the fuel bed.

29. In an automatic stoker, a fuel retort or trough, a sectional twyer at one side of the fuel retort or trough, each twyer section being provided with corrugated fuel supporting bars stepped upwardly from said side of the fuel retort or trough and arranged substantially parallel therewith; and a sectional twyer at the opposite side of the fuel retort or trough, each twyer section being provided with corrugated fuel supporting bars stepped downwardly from the said side of the fuel retort or trough and arranged substantially parallel therewith.

30. In an automatic stoker, a fuel retort or trough, and sectional twyers at the sides of said retort, the sections of said twyers each comprising side walls provided with air passages, end walls, and fuel supporting bars spaced apart and extending in the direction of the length of the retort, said bars being detachably secured on said end walls.

31. In an automatic stoker, a fuel retort or trough, and sectional twyers at the sides of said retort, the sections of said twyers each comprising a hollow body, upwardly extending plates detachably secured to the ends of said body, side walls detachably secured on said plates, and relatively small corrugated fuel supporting bars secured on said plates in stepped relation to provide air spaces.

32. In an automatic stoker, a fuel retort or trough, and sectional twyers at the sides of said retort, the sections of said twyers each comprising side walls provided with inwardly converging air passages, and relatively small corrugated fuel supporting bars arranged in stepped relation and extending in the direction of the length of said retort.

33. In an automatic stoker, a fuel retort or trough, and twyers at the sides of said retort each comprising a plurality of substantially rectangular hollow members disposed in end to end relation, and a plurality of relatively small fuel supporting bars on each of said members and extending in the direction of the length of said retort, said bars being arranged in stepped relation to provide air passages, the bars being corrugated to increase the total section of the air passages and to provide external ash collecting recesses.

34. The combination in a locomotive, a furnace provided longitudinally thereof with a central refuse discharge passage and a series of alternating twyers and fuel retorts on each side of said passage, said twyers successively decreasing in elevation from the sides of the furnace toward said

refuse discharge passage to provide an inclined fuel bed, and means for feeding fuel through said retorts to said fuel bed.

35. The combination in a locomotive, a furnace having an inclined fuel bed comprising two opposed series of alternating twyters and retorts, said twyters successively decreasing in elevation from the sides of the furnace toward a medial fore and aft line thereof and a plurality of grates providing a longitudinal refuse discharge opening at the center of the furnace, automatic means for feeding fuel through said retorts to said fuel bed, and automatic means for crushing and discharging the solid products of combustion delivered through said opening from said fuel bed.

36. The combination in a locomotive, a furnace having an inclined fuel bed comprising a plurality of fuel retorts successively decreasing in capacity from the sides of the furnace toward a medial fore and aft line thereof and twyters on both sides of said retorts, and means for feeding fuel through said retorts to said fuel bed.

37. The combination in a locomotive, a furnace having an inclined fuel bed comprising a plurality of alternating twyters and retorts extending longitudinally of the furnace, said twyters successively decreasing in elevation from the sides of the furnace toward a medial fore and aft line thereof, and means for feeding fuel through said retorts to said fuel bed, the retorts decreasing in cross-section toward the center of the furnace.

38. In an automatic stoker, a plurality of fuel retorts successively decreasing in capacity from the sides of the furnace toward a medial fore and aft line thereof, twyters on both sides of said retorts, and means for feeding fuel through said retorts to said twyters comprising a reciprocatory member for each retort and a lever connected with said members and arranged to oscillate about a central pivot.

39. In an automatic stoker, a plurality of fuel retorts successively decreasing in capacity from the sides of the furnace toward a medial fore and aft line thereof, twyters on both sides of said retorts, and means for feeding fuel through said retorts to said twyters comprising reciprocatory members for each retort having successively decreasing strokes from the sides of the furnace toward the center thereof.

40. In an automatic stoker, a plurality of fuel retorts successively decreasing in capacity from the sides of the furnace toward a medial fore and aft line thereof, twyters on both sides of said retorts, means for feeding fuel through said retorts to said twyters comprising a plurality of fuel feeding members disposed within the retorts, and having successively decreasing strokes respectively

from the sides of the furnace toward the center thereof, and means imparting motion to said fuel feeding members comprising a lever adjustably connected with said members and arranged to oscillate about a central pivot.

41. In combination, a furnace, a fuel bed in said furnace comprising two opposed series of alternating twyters and retorts, said twyters successively decreasing in elevation from the sides of the furnace toward a medial fore and aft line thereof, a refuse discharge opening at the bottom of said fuel bed and a refuse chamber in the furnace arranged below said refuse discharge opening, means for feeding fuel through said retorts to said fuel bed, and means in said refuse chamber for ejecting the refuse delivered thereto through said opening.

42. In combination, a furnace, a fuel bed in said furnace comprising two series of alternating twyters and retorts, said twyters successively decreasing in elevation from the sides of the furnace toward a medial fore and aft line thereof, a refuse discharge opening at the bottom of said fuel bed and a refuse chamber in the furnace arranged below said refuse discharge opening, means for feeding fuel through said retorts to said fuel bed, means in said refuse chamber for ejecting the refuse delivered thereto through said opening, and means for regulating the speed of ejection of the refuse.

43. In combination with a furnace, a V-shaped fuel bed in said furnace comprising a plurality of alternating twyters and retorts, said twyters successively decreasing in elevation from the sides of the furnace toward the medial line thereof, a fuel hopper at the outer end of each retort, means advancing the fuel from said hopper to said fuel bed, and means supplying fuel to said hopper.

44. In combination with a furnace, a V-shaped fuel bed in said furnace comprising a plurality of alternating twyters and retorts, said twyters successively decreasing in elevation from the sides of the furnace toward the medial line thereof, a fuel hopper at the outer end of each retort, means advancing the fuel from said hopper to said fuel bed, means supplying fuel to said hopper, and means for driving said fuel feeding means operatively connected with said hopper supplying means to drive the same.

45. In combination with a furnace, a V-shaped fuel bed in said furnace comprising two opposed series of alternating twyters and retorts, said twyters successively decreasing in elevation from the sides of the furnace toward the medial line thereof, a hopper supplying fuel to the outer end of each retort, means advancing the fuel through the retorts to said fuel bed, conveyor means supplying fuel to the fuel hopper, means supplying fuel to the conveyor means, and

means for agitating the fuel to insure its movement onto the conveyor means.

46. In combination with a furnace having a V-shaped fuel bed comprising a plurality of longitudinally extending retorts successively decreasing in depth from the longitudinal sides of the furnace toward the medial line thereof and twyers on both sides of the retorts, a fuel hopper supplying fuel to the outer ends of the retorts, means advancing the fuel through the retorts to the fuel bed, conveyor means supplying fuel to the fuel hopper, and flexible connections between the conveyor means and the fuel hopper.

47. In combination with a locomotive and fuel tender therefor, a furnace on the locomotive provided with a fuel bed comprising two series of alternating twyers and fuel retorts extending longitudinally of the furnace, said twyers successively decreasing in elevation from the sides of the furnace toward the medial line thereof, means feeding fuel through said retorts to said fuel bed, and means supplying fuel from said fuel tender to said fuel feeding means.

48. In combination with a locomotive and fuel tender therefor, a furnace on the locomotive provided with a fuel bed comprising two series of alternating twyers and fuel retorts extending longitudinally of the furnace, said twyers successively decreasing in elevation from the sides of the furnace toward the medial line thereof, means feeding fuel through said retorts to said fuel bed comprising main and secondary fuel feeding members disposed substantially throughout the length of each retort, and means supplying fuel from the fuel tender to said fuel feeding means.

49. In combination with a locomotive and

fuel tender therefor, a furnace on the locomotive provided with a fuel bed comprising two series of alternating twyers and fuel retorts extending longitudinally of the furnace, said twyers successively decreasing in elevation from the sides of the furnace toward the medial line thereof, means feeding fuel through said fuel retorts to said fuel bed, and means supplying fuel from the fuel tender to said fuel feeding means, said fuel supplying means comprising main and secondary fuel feeding members on the bottom of the fuel tender.

50. In combination with a locomotive and furnace therefor, a fuel bed in said furnace comprising a plurality of alternating twyers and retorts disposed longitudinally of the furnace, said twyers successively decreasing in elevation from the sides of the furnace toward a central discharge opening thereof, a conduit arranged longitudinally of the locomotive for supplying air to said twyers and receiving a forced draft by motion of the locomotive, and means arranged in said conduit for supplying steam with the forced air draft.

51. In an automatic stoker, a plurality of fuel retorts or troughs, and a plurality of sectional twyers alternating with said fuel retorts or troughs and successively decreasing in elevation from a wall of the furnace toward the interior thereof, the twyer sections each being provided with a plurality of detachable fuel supporting bars arranged in stepped relation and extending in the direction of the length of the twyer.

In testimony whereof I have signed this specification.

MAURICE RATEL.
